UNITED STATES PATENT OFFICE.

WILLIAM N. SEWELL, OF WINCHESTER, KENTUCKY.

MATCH-SAFE.

1,004,090.

Specification of Letters Patent. Patented Sept. 26, 1911.

Application filed December 17, 1910. Serial No. 597,854.

To all whom it may concern:

Be it known that I, WILLIAM N. SEWELL, a citizen of the United States, residing at Winchester, in the county of Clark and 5 State of Kentucky, have invented a new and useful Match-Safe, of which the following is a specification.

This invention relates to special receptacles, and more particularly to those known 10 as match safes; and the object of the same is to produce a receptacle of this kind adapted to contain a match box of the type now on the market.

To this end the invention consists in the 15 details of construction hereinafter described and claimed, and as shown in the drawings wherein:—

Figure 1 is a perspective view of this match safe complete, and Figs. 2 and 3 are 20 vertical sections through the same at right angles to each other. Fig. 4 is a perspective view of the casing of the match box torn away at one end as necessary for use with this safe. Fig. 5 is a plan view of the blank 25 from which the body is made, and Fig. 6 a similar view of the blank which forms the bottom of said body, while Fig. 7 is a similar view of the blank which forms the band around said bottom. Fig. 8 is a detail of the 30 flap. Figs. 9 and 10 are plan views of the blanks respectively forming the wall of the cover and the partition therein. Fig. 11 is a detail of the support.

This match safe is by preference made entirely of paper board of such weight that it 35 may be scored and folded on the dotted lines illustrated in the views which show the blanks, although of course it is possible to make it of wood, metal, or other material 40 possessing sufficient pliability and other attributes to adapt it for this use. The present illustration shows this improved safe as proportioned so as to receive a match box found in common use today upon the market, 45 whereof the casing lettered M in Fig. 4 and sand-papered along one side as at S will be slid slightly off the match box proper and torn away a little at one end as shown at m; then it will be slipped back onto the box and 50 the whole stood upright within the safe as best seen in Fig. 2, whereby the matches within the box will drop to its lower end, out the opening at m, and into a tray at the bottom of the safe which is normally closed 55 by the flap shown in Fig. 8, and from the

tray the operator picks the matches one by one, first raising the flap with his finger.

It is obvious that the match safe can be proportioned so as to contain match boxes of other size than that illustrated. 60

The body 10 of the safe is formed from the blank shown in Fig. 5 and comprises three panels 11, 12 and 13 and two flaps 14 at the outer edges of the outermost panels 11 and 13 which are of such width that when this 65 blank is folded into shape as seen in Fig. 1 a vertical space remains between the edges of the flaps and the sand papered surface S of the match box casing M is exposed. The lower end of the panel 11 which will stand 70 at the front of the box is cut away as at 15 to register with the torn off portion m of the casing M and forms the outlet from the body into the tray. The latter is formed of a bottom shown in Fig. 6 and a band shown in 75 Fig. 7. The bottom comprises a rectangular center 21 and four edge flaps 22 notched at their corners 23 so that they may all be turned about at right angles to the center. The band comprises a central panel 24, 80 which stands across the front of the tray as best seen in Fig. 1, two side panels 25, and two end flaps 26. The flaps of the bottom are bent up, the band is bent around them with its flaps 26 at the rear of the body, and 85 the parts are stapled or otherwise secured rigidly together and to the body as at 27. The flap 28 shown in Fig. 8 is then attached by a hinge 29 to the front of the body panel 11 above its cut away portion 15, and obviously drops into closed position over the 90 tray as will be clear. The cover comprises a band forming its wall and a cross partition, the blanks for these members being shown in Figs. 9 and 10. The wall includes four 95 panels 31, 32, 33 and 34, and an end flap 35 adapted to be connected to the remote end of the first panel 31; and the partition includes a rectangular center 36 and four side flaps 37 notched as at 38 at their corners. These 100 flaps are turned upward at right angles to the center, the band passed around them, and the members secured together by staples 39 or otherwise. It is obvious that this form of cover may be slipped onto the open upper 105 end of the body 10 so that the center 36 closes said body and serves also as the bottom of a tray open at the top and into which dead matches can be thrown. At any time this cover may be withdrawn when it is neces- 110

sary to remove an empty match box and insert a new one.

The support best seen in detail in Fig. 11 may be and by preference is of wire bent 5 practically into the shape of a hair pin having two arms 40 with a bend 41 between them at their upper ends and reversely bent feet 42 at their lower extremities. This support is laid against the back of the body 10 (see Figs. 2 and 3) with its feet hooked inside the flaps 26 of the band around the bottom thereof and possibly hooked under the lower edge of the rear panel 13 of the body, its arms 40 rise thence along the back 15 of the safe and extend above the upper end of the body, and when the cover is applied the bend 41 of the support may be passed between one of the panels of its wall and one of the flaps 37 of its partition as seen in 20 Fig. 1, and thereby the cover will be frictionally held in place so that the live matches or the match box will not be dislodged if the safe should be accidentally knocked over.

The folding of paper blanks on their score 25 lines is so well known in the art of making boxes that I have indicated such scores only by dots and have not elaborated upon the process of folding and connecting the parts. I show and describe staples as connecting 30 means, though it is obvious that glue, rivets or other equivalent devices might be employed. Where necessary the corners are notched as has been explained, and the notches may be beveled as indicated in Fig. 7 35 and as some manufacturers prefer.

The paper board or other material of which the safe is composed may be treated to render it more sightly, or even fire-proof, and it may bear illustrative or advertising 40 matter.

It is hardly necessary to amplify the mode of using this safe, further than to say that the casing of the match box is torn away as at *m*, the cover lifted off the safe, the match 45 box and its casing inserted so that its opening *m* registers with the opening 15 into the tray, the cover replaced, and the whole hung

against the wall as by a nail therein which passes under the band 41 of the support. Obviously after the matches are all consumed, the old match box is removed and a new one substituted.

What is claimed as new is:—

1. A match safe comprising an upright body composed of three panels and two flaps, the combined width of the latter being less than that of any panel so as to leave a space between their edges through which the scratching surface of the inclosed match box is exposed, the lower end of the front 60 panel being cut away; a bottom secured to and larger than the lower end of said body and its front end forming a tray communicating with said cut away portion, a band around the bottom secured to said flaps and 65 spanning the lower end of the space between them; and a cover removably closing the upper end of said body and spanning the open upper end of the space between the adjacent edges of said flaps. 70

2. In a match safe, the combination with an upright rectangular body having an outlet opening at its lower end, a bottom secured thereto and having a tray registering with said opening, and a top removably 75 closing the upper end of the body and comprising a surrounding band and a partition across the interior thereof between its upper and lower edges; of a support consisting of a piece of wire bent into two arms standing 80 against the rear of the body, having feet at their lower extremities secured inside the band of said bottom, and having its bent portion projecting through the cover between the rear wall thereof and one edge of 85 its partition.

In testimony that I claim the foregoing as my own, I have hereto affixed my signature in the presence of two witnesses.

WILLIAM N. SEWELL.
